FIG. 9.

UNITED STATES PATENT OFFICE.

OSCAR L. OLSON, OF BRAHAM, MINNESOTA, ASSIGNOR OF TWO-THIRDS TO ELMER E. HEGSTROM, OF BRAHAM, MINNESOTA.

HITCHING DEVICE.

1,268,796.

Specification of Letters Patent. Patented June 4, 1918.

Application filed April 2, 1918. Serial No. 236,151.

To all whom it may concern:

Be it known that I, OSCAR L. OLSON, citizen of the United States, residing at Braham, in the county of Isanti and State of Minnesota, have invented a new and useful Hitching Device, of which the following is a specification.

My invention relates to hitching devices and the object is to provide means whereby the rope of a bridle or halter can be quickly, easily and effectively secured to or loosened from a manger or other place where a horse or other animal is wanted fastened.

In the accompanying drawing, Figure 1 is a front view of the device secured to the top edge of a manger wall 5. Fig. 2 is a right hand side view of Fig. 1. Fig. 3 is a view similar to Fig. 1 but with the front plate 3 removed. Fig. 4 is a section on the line 20 4-4 in Fig. 2. Fig. 5 is a section on the line 5-5 in Fig. 1, but showing the plunger 11 in its upper position. Fig. 6 is a section similar to that in Fig. 5 but showing the plunger 11 in its lower position. Fig. 7 is a 25 section on the line 7-7 in Fig. 3. Fig. 8 is a detail view of the top part of Fig. 7, but showing how a rope is clamped or pinched in the device. Fig. 9 is a detail top end view of the lever 20.

30 Referring to the drawing by reference numerals, 1 designates the main body portion of the device having an integral back plate 2 and a removable front plate 3. The body 1 is let into a notch 4 (see Fig. 3) in the manger or other board or plank 5 where the device is to be placed, and is secured by bolts 6 which pass through both plates 2 and 3 and the woodwork 5. The front plate 3 is secured to the main body 1 by machine screws 7 screwed into holes 8 (see Fig. 3).

The body portion 1 of the device is provided with two vertical slots or gaps 9 and 10, in the former of which is slidably 45 mounted a plunger 11 having at its upper end a horizontal rope engaging extension 12 adapted to engage the upper side of a rope 13 (see Fig. 8) in a groove 14 in its under side. A spring 15 tends to hold the plunger 50 11 in its upper position, as shown in Fig. 5, but it is normally held in its lower position by a bolt 16 engaging the notch 17 in the side of the plunger. Said bolt 16 is slidably mounted in the main body 1 (see Fig. 4) and is held in engaging position

with the notch 17 by a spring 18. The operator can release the bolt 17 by pushing a finger plate 19, with which it is integral, to the left; which allows the plunger 11 to rise, and thus releases the rope 13. The spring 60 18 should be sufficiently stiff to prevent accidental moving of the plate 19 by an animal secured with the hitching device.

In the slot or gap 10 is pivotally mounted at 20^a a lever 20 which is normally held 65 in a vertical position (see Figs. 3 and 7) by a spring 21. In one side of said lever is fixed a pin 22 adapted to slide in a segmental slot 23 in a partition 24 between the two gaps 9 and 10. Said pin 22 is long 70 enough to reach into the gap 9 and engage a square or oblong aperture 25 in the plunger 11. The front plate 3 is provided with a notch 26 to allow room for the rope 13 (see Figs. 1, 7 and 8) and the back plate 75 2 is provided with a deep notch 27 and the lever 20 is also provided with a notch 28 to clear the terminal of the notch 27 when said lever is swung to the position shown in Fig. 6. The top end of the lever 20 is pro- 80 vided with angular corrugations 29 (see Fig. 9) corresponding to the strands of the rope which is then more firmly pinched between the lever 20 and the groove 14.

In the operation of the device, when it is 85 desired to secure a bridle or halter rope in the device the plunger 11 is in its upper position, as shown in Fig. 5. The rope to be secured is stretched between the two hands and is brought to bear down upon the lever 20 and pulled rearwardly so as to swing said lever 90 20 to the position shown in Fig. 6. This movement causes the pin 22 to move the plunger 11 down until the spring-pressed bolt 16 engages the notch 17. When this is 95 done the rope is released by the hand and is moved up into the notch 14 by the lever 20 which is raised by a spring 21. The lever and rope then assume the positions shown in Fig. 8, where it is obvious that the rope 100 could not be pulled out to the left (the left end of the rope being the one secured to the animal). To release the rope it is only necessary to move the finger plate 19 to the left against the spring 18 until the bolt 16 disengages the notch 17, which allows the plunger 11 to spring up, thus disengaging the notch 14 from the rope and leaving the latter loose upon the top end of the cam acting lever 20.

What I claim is:

1. A hitching device comprising a suitable casing, a lower pinching member pivoted within the casing, a vertically slid-
5 able upper pinching member mounted within the casing and adapted to pinch a rope between itself and the lower pinching member, and means for releasing the upper pinching member when so desired.
- 10 2. A hitching device comprising a suitable casing, an upper rope pinching member adapted to be lowered into an engaging position and adapted to be raised into disengaging position, a lower cam acting pinching lever pivoted within the casing and adapted to pinch a rope between itself and the upper pinching member when the latter is in engaging position, operative connection between the upper pinching member and the lower pinching lever for bringing the former into engaging position by a swinging movement of the latter on its pivot.
- 15 3. A hitching device comprising a suitable casing, a lower pinching lever pivoted within the casing, a vertically slidable upper pinching member mounted in the casing and adapted to pinch a rope between itself and the lower pinching lever when in a lowered position, spring-actuated means for causing the upper pinching member to assume an upper disengaging position, operative connection between the upper pinching member and the lower pinching lever for bringing the former into engaging position by a
20 swinging movement of the latter on its pivot, hand controlled means for holding the upper pinching member in and for re-

Copies of this patent may be obtained for five cents each, by addressing the "Commissioner of Patents, Washington, D. C."

leasing it from its lowered engaging position.

4. The structure specified in claim 3, said hand controlled means having a spring throwing it into engagement with the upper pinching member and a finger catch to take hold of to disengage it against the resistance of said spring. 40 45

5. A hitching device comprising a frame adapted to be secured to a manger or other stationary object, two jaws mounted in the frame and adapted to grip a rope or other hitching strap between them; one of said jaws being pivoted and provided with a corrugated cam face by which to engage any part of the hitching strap, a spring arranged to swing said cam into engaging position, the other jaw being mounted to slide to and from the cam jaw, a spring closed finger catch arranged to engage and hold the slide-
50 able jaw in active position, a spring arranged to retract said sliding jaw into idle position when the finger catch is disengaged 55 from it.

6. The structure specified in claim 5 and operative connection between the two jaw members whereby the swinging of the cam-shaped jaw into idle position causes the other jaw to move into active position and interlock automatically with the finger catch, and thus be ready to meet one side of the strap when the cam jaw is returned by its spring into active position against the other side of the strap. 60 65 70

In testimony whereof I affix my signature.

OSCAR L. OLSON.
